UNITED STATES PATENT OFFICE.

FRANCIS E. GRIFFETH, OF ATHENS, GEORGIA.

SAD-IRON HOLDER.

958,634.

Specification of Letters Patent.

Patented May 17, 1910.

Application filed May 14, 1909. Serial No. 495,956.

To all whom it may concern:

Be it known that I, FRANCIS E. GRIFFETH, a citizen of the United States, residing at Athens, in the county of Clarke and State 5 of Georgia, have invented certain new and useful Improvements in Sad-Iron Holders; and I do hereby declare the following to be a full, clear, and exact description of the invention, such as will enable others skilled 10 in the art to which it appertains to make and use the same.

My invention relates to sad-iron holders adapted to support the iron in an upright position when used as a sad-iron and also 15 in an inverted position so that it may be used as a stove for cooking purposes.

The object of the invention is to provide a holder of this kind which is very simple in construction, can be manufactured economically and will hold the iron securely 20 against slipping off in any direction when supported thereby in either an upright or inverted position.

The invention consists in the features of 25 construction and combination of parts hereinafter described and specified in the claim.

In the accompanying drawing illustrating the preferred embodiment of my invention: Figure 1 is a side view of the stand showing 30 an iron supported in an upright position thereon. Fig. 2 is a similar view of the holder showing the iron supported in an inverted position. Fig. 3 is a plan view of the holder alone, and Fig. 4 is a broken sectional view 35 on the line $x-x$ of Fig. 3 showing particularly the connection between the posts and the plates.

The holder illustrated in the drawing comprises a base-plate 1 and an upper U-shaped 40 plate 2 arranged horizontally and supported substantially parallel to each other, one above the other, by upright posts 3. The shape of said plates conform generally to the shape of an iron, there being three posts 45 3, one arranged at the forward end and two at the respective corners of the rear end of the base-plate. Each of the posts consists of a rod of metal which is preferably round in cross-section and which has its ends reduced, 50 as at 3^a, in Fig. 4. These reduced portions are passed through openings in the base-plate and U-shaped plate, respectively, and have their extremities upset whereby rigid connections are made with said plates. The 55 reduced portions at the lower ends of

said posts are rounded, extend some distance below the base-plate and constitute feet 3^b which support said plate above the surface on which the holder is placed.

The U-shape of the plate 2 leaves a central slot 4 which is closed at the front end of said plate but open at its rear end. This slot allows the handle 5 of the iron 6 to extend below said plate when the iron is placed on the same in an inverted position. 60 The U-shaped plate is spaced from the base-plate so as to support the handle of the iron above and out of contact with said base-plate whereby the wooden hand-piece, usually fitted on electrically heated irons for 65 which my holder is especially designed, will not be rubbed, scratched or otherwise marred as would result if it did come in contact with the base-plate or was supported thereby. 75

In order to prevent the iron from accidentally slipping off of the holder rearwardly when in an inverted position, upwardly extending lugs 7 are arranged at the rear end of the U-shaped plate, one at each side of the 80 central slot. When the iron is in this position, it will be impossible for it to slip off in either a forward or lateral direction by reason of the U-shape of said upper plate. In order to retain the iron upon the 85 holder in an upright position, two upwardly extending lugs are arranged on each side of the U-shaped plate, one of said lugs 8 being placed at or near the rear corner and the other 9 near the front end of said plate. 90 These lugs 8 and 9 prevent the iron from slipping off in either a forward or lateral direction, when in an upright position. The lugs 7 prevent said iron from slipping off rearwardly when in this position as well as 95 when in an inverted position.

I do not limit myself to the details of construction shown and described herein. For instance, while I have shown the lugs 7 and 8 meeting at the rear corners of the 100 U-shaped plate, said lugs may be spaced some distance apart and still perform their intended functions. I, therefore, reserve the right to make such changes as fairly fall within the scope of my invention as defined 105 by the claim.

I claim:—

A sad iron holder comprising a base plate, a U-shaped plate adapted to support said iron in either an upright or inverted 110

position, lugs at both sides and both ends of said U-shaped plate for the purposes specified, the lugs at the open end of said plate serving to prevent the horizontal displacement of the iron in that direction when in either an upright or inverted position, and upright posts connecting said plates and extending through said base plate and

forming feet which support said plate above the surface on which the holder is placed. 10

In testimony whereof, I affix my signature, in presence of two witnesses.

FRANCIS E. GRIFFETH.
